UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

COWL-LAMP.

1,217,925.

Specification of Letters Patent. Patented Mar. 6, 1917.

Application filed March 27, 1916. Serial No. 86,866.

To all whom it may concern:

Be it known that I, HARRY A. DOUGLAS, citizen of the United States, residing at Bronson, in the county of Branch and State 5 of Michigan, have invented a certain new and useful Improvement in Cowl-Lamps, of which the following is a full, clear, concise, and exact description, reference being had to the accompanying drawings, forming a 10 part of this specification.

My invention relates to sockets for incandescent lamps, a structure involving my invention being of particular service where a cowl is used to shield a lamp bulb and to 15 limit the passage of light therefrom.

The device of my invention is inclusive of a tubular shell secured at one end to a plug of insulation that constitutes a contact carrier for including the lamp in circuit and a 20 flange at the other end of the shell, the outer marginal portions of which flange being preferably continued to form mounting lugs for the socket and a short split tubular portion or rim upon which the cowl may be 25 slipped and on which the cowl may be turned to define the direction in which light is to emanate from the lamp.

I will explain my invention more fully by reference to the accompanying drawing 30 showing the preferred embodiment thereof and in which Figure 1 is a view in elevation of a structure embodying the invention, a support for the lamp socket being indicated in section; Fig. 2 is a view similar to Fig. 35 1 excepting that the lamp socket and the cowl are shown in section; Fig. 3 is a view on line 2—2 of Fig. 2, the plug and lamp being shown in full view while other parts are shown in section; Fig. 4 is a view on line 40 4 4 of Fig. 1; and Fig. 5 is a perspective view.

Like parts are indicated by similar characters of reference throughout the different figures.

45 The tubular shell 1 has a plug 2 secured to one end thereof, this plug carrying contacts 3, 4 working within spring barrels 5, 6, the rear ends of the contacts having enlargements which engage the inturned front ends 50 of the spring barrels so that the contacts are prevented from leaving engagement with the barrels. These spring barrels are connected with circuit terminals, as usual.

Coiled springs 7 and 8 are disposed in the

spring barrels 5, 6 for the purpose of thrusting the contacts 3 and 4 outwardly. The shell 1 has bayonet recess formations 9, 10 by means of which a lamp may be held within the socket, the base of the lamp carrying bayonet pins 11 for reception within the 60 bayonet recesses and when the lamp is thus engaged with the shell 1 the contacts 3 and 4 are thrust, by the springs 7 and 8, into engagement with the contacts 12 and 13 carried by the base of the lamp and constituting terminals of the lamp filament 14. The bayonet recesses 9 are desirably formed by outward depressions in the forward end of the shell instead of being in the nature of slots cut through the shell. 70

The lamp receiving end of the shell is spread outwardly to form a flange 15 that constitutes an abutment to define the position of the shell with respect to the mounting 16 which may be a dashboard in an automobile, for example. The annular flange 15 is extended to form a mounting lug or lugs 17 extending laterally of the shell and which may be provided with screw holes for the reception of screws 18 employed to fasten the fastening lugs upon the dash board or other support. The flange also has a short forwardly projecting tubular extension 19, that is substantially co-axial with the shell and which extension is split where 85 the lug formation occurs in order that the flange, the lug formation and the tubular extension may be integrally formed with the balance of the shell 1, the extension 19 being discontinued where the lugs 17 occur 90 so that such extension is divided into two parts that are separated substantially the width of the lugs. The cowl or hood 20 may be slipped upon the short tube 19 and turned thereon, the light from the lamp bulb passing through the opening or passage 21 in the cowl or hood to shine directly upon the object to be illuminated. 95

Having thus described my invention I claim as new and desire to secure by Letters Patent the following:—

A lamp socket including a shell having a contact carrying plug in one end thereof and having integrally formed therewith at its other end a flange, a fastening lug formation projecting from the flange and laterally of the shell, and a hood receiving tubular extension of the flange at the outer edge 105

of the flange and projecting forwardly therefrom and being substantially co-axial with the shell, the hood receiving tubular extension being discontinued where the fastening lug formation projects from the flange substantially to an extent equaling the width of such fastening lug formation; in combination with a lamp held within the socket and a hood supported by the tubular extension

of the flange and having a light transmitting opening or passage.

In witness whereof, I hereunto subscribe my name this 16th day of March, A. D. 1916.

HARRY A. DOUGLAS.
